AIRMAN'S HELMET

Edward G. Griffiths, Maywood, N.J., assignor to Camloc Fastener Corporation, Paramus, N.J., a corporation of New York

Filed Oct. 26, 1961, Ser. No. 67,269

Term of patent 14 years

(Cl. D3—13)

FIG. 1

FIG. 2

FIG. 1 is a perspective view of an airmen's helmet showing my new design the side opposite being a mirror image thereof; and

FIG. 2 is a perspective view thereof as it appears with the face plate portion in raised position.

The essential feature of my design resides in the portions shown in full lines on the drawing.

This application is a continuation-in-part of my application Serial No. 59,572, filed March 1, 1960, now abandoned.

I claim:

The ornamental design for an airmen's helmet, as shown and described.
